United States Patent Office

Des. 219,004
Patented Oct. 27, 1970

219,004

BRASSIERE OR SIMILAR ARTICLE

Carol Therese Ameche, 305 S. Wesley Ave.,
Oak Park, Ill. 60302

Filed Apr. 15, 1969, Ser. No. 16,751

Term of patent 14 years

Int. Cl. D2—02

U.S. Cl. D2—24

The figure is an isometric view of a brassiere showing my design, portions of the front and side not shown being similar to that shown, the back being conventional and plain.

What I claim is:

The ornamental design for a brassiere or similar article, substantially as shown and described.
